UNITED STATES PATENT OFFICE.

SAMUEL WEINSTEIN, OF CHICAGO, ILLINOIS.

TRAY.

1,135,088.

Specification of Letters Patent. Patented Apr. 13, 1915.

Application filed May 26, 1913. Serial No. 770,075.

To all whom it may concern:

Be it known that I, SAMUEL WEINSTEIN, a citizen of the United States, and a resident of the city of Chicago, in the county of Cook 5 and State of Illinois, have invented certain new and useful Improvements in Trays; and I do hereby declare that the following is a full, clear, and exact description of the same, reference being had to the accompanying 10 drawings, and to the numbers of reference marked thereon, which form a part of this specification.

This invention relates more particularly to that class of trays used by jewelers, 15 wherein a small and light construction is desirable.

Heretofore such trays have been usually constructed of a small wooden frame which afforded the edge for the tray, and with a 20 cloth covered bottom of light straw board or the like fastened thereon.

It is an object of this invention to construct a tray frame of metal, preferably for lightness, of aluminum, and with a fabric, 25 such as felt or flannel, stretched tightly thereacross and secured therein to afford a bottom for the tray.

It is also an object of this invention to construct a device in which the fabric bottom 30 is retained at its edges frictionally within the frame by means of a wire sprung resiliently therein.

It is also an object of this invention to provide a tray frame consisting of interfitting members affording a resiliently closed 35 recess adapted to receive a retaining wire for a fabric bottom therein.

It is also an object of this invention to provide a device wherein the ends and side 40 members are suitably brazed together and afford a continuous groove for the reception of the attaching means for a fabric bottom.

It is furthermore an object of this invention to provide a device constructed of suitable 45 interfitting members whereby sharp edges and corners are avoided, and one in which the fabric bottom contacts with the support upon which the tray may be placed to prevent possibility of scratching the support.

It is finally an object of this invention to construct a cheap, simple, and durable device of light weight, capable of easy manufacture, and assembly, and one wherein the

tray bottom may be readily detached for 55 renewal.

The invention (in a preferred form) is hereinafter described and more fully pointed out and defined in the appended claims.

In the drawings: Figure 1 is a top plan 60 view of a tray embodying the principles of my invention. Fig. 2 is a central section on line 2—2 of Fig. 1. Fig. 3 is a fragmentary bottom plan view partly in section, showing the relation of the assembled elements. Fig. 65 4 is a fragmentary enlarged sectional detail taken on line 4—4 of Fig. 1.

As shown in the drawings: 1, indicates the side and end frame members of a tray, which are composed of an integral top or cover 70 member 2, having the extremities 3, thereof curved inwardly and upwardly for a short distance. An integral inner member, having the walls 4, and centrally arched portion 5, affording a closed recess 6, is engaged in 75 said outer member 2, by sliding the same longitudinally within said member 2, and is retained therein by the friction of the engaging faces of the inner and outer members respectively. The top walls of said side 80 and end members meet at the corners along a diagonal line and are suitably brazed together to afford a substantially integral construction having a continuous groove or recess 6, extending completely therearound. 85

As shown more clearly in Fig. 3, the various portions of the inner element are of a less length than the outer element 2, so that such portions do not meet or contact one another at the corners, thereby obviating the 90 possibility of distortion of the inner elements when the outer elements are brazed together at the corners. A piece of fabric 7, is stretched over the under side of said integral frame construction, and a strip of 95 wire 8, cut to suitable length is laid over the fabric and then pressed inwardly past the resilient edges 3, of the recess 6, and serves to retain the fabric edge therein.

The operation is as follows: The side and end members composed of the telescoped inner and outer sections are cut to suitable length, depending upon the size of the tray desired to form, and the angled ends thereof are then suitably brazed together at the corners of the construction. The outer member 2, which completely incloses the inner member, is japanned or enameled to afford a 100 105

suitable finished appearance. When about to affix the fabric bottom to the frame, the frame is inverted upon a suitable support and the fabric 7 laid thereacross, whereupon the wire 8 is forced downwardly into the recess forcing the edge of the fabric inwardly therewith and binding the same frictionally therein, causing the same to be stretched tightly over the frame. Said wire 8, also serves to bind the end and side members of the frame construction together. When the fabric becomes worn or torn the wire may be removed and a new strip of the same may be readily attached in the manner described.

15 I claim as my invention:

1. A device of the class described, embracing a channel member having its walls curved and turned inwardly and spaced apart, a resilient member inserted within said channel member and shaped to afford a recess closed at its inner end and with an open front registering with the opening in said channel, a strip of fabric stretched across said channel member, and means in-

serted into the recess in said resilient member to retain the edges of the fabric tightly engaged in the channel member. 25

2. In a device of the class described, hollow members affording a frame, the walls of said members curved and turned inwardly 30 affording a continuous slot therein, resilient members engaged within said hollow members and arched to afford a closed recess and having an open front in register with the slot in said hollow members and with the 35 walls of said resilient member shaped to fit closely within the inturned walls of said hollow member, and means engaging the edges of a strip of fabric stretched across the frame to press said edges into said closed recess to hold the fabric securely in place. 40

In testimony whereof I have hereunto subscribed my name in the presence of two subscribing witnesses.

SAMUEL WEINSTEIN.
